CLAY GUN

August F. Giese, Jr., Gary, Ind.

Application May 24, 1940, Serial No. 336,893

3 Claims. (Cl. 266—42)

My invention relates to clay gun structures adapted particularly for plugging up tapping holes of blast furnaces to shut off the flow of molten metal therefrom after the furnace is through with a tap.

Clay gun structures usually comprise a cylinder for receiving a clay mixture to be discharged, some discharge means as for example a piston operable within the cylinder, power means for operating the discharge means, and a nozzle element extending from the end of the cylinder for directing the discharged clay into the tapping hole.

The important object of my invention is to provide an arrangement in which the cylinder and the driving means are mounted in front of the furnace at one side of the runner trough and with the axis of the cylinder at right angles with the trough, and with an angular nozzle permanently secured to the cylinder end with its free end over the runner trough, together with means for rotating the cylinder for swing of the nozzle with its discharge end into the trough for discharge of clay therefrom into the tapping hole, or for swing of the nozzle into position above the runner trough during the casting of metal from the furnace. Such improved structure and arrangement will eliminate objectionable conditions, such as leakage and wear, exposure of the gun structure to heat and splashing molten metal, and costly care and repairs.

The various features of my invention are incorporated in the structure shown on the drawings, in which drawings:

Figure 1 is a plan view of the gun structure mounted in front of a furnace;

Figure 2 is a front elevation of the gun structure with the runner trough shown in section;

Figure 3 is an end elevation of the gun structure with furnace parts shown in section, and showing one arrangement for effecting rotation of the cylinder for swing of the nozzle into discharging position or idle position; and

Figure 4 is a front elevation of the power end of the gun showing a modified arrangement.

On the drawings 10 indicates a furnace having the tap hole 11, and 12 indicates the runner trough communicating with the tap hole, 13 indicating the usual columns around the furnace for support thereof.

The gun structure comprises a cylinder 14 in which a piston 15 is operable. An intermediate member 16 in axial alignment with the cylinder provides the head 17 for the cylinder and a guide bearing for the piston rod or shaft 18, the mem-

ber 16 being detachably secured to the cylinder as by means of bolts 19. At its outer end intermediate member 16 has the flange 20 to which is secured the flange 21 of an annular bearing hub 22 which is journaled in a supporting bearing structure 23. A bearing structure 24 journals the outer end of the cylinder 14 between aligning flanges or collars 25 on the cylinder. The cylinder portion with the intermediate member 16 secured thereto is thus journaled for rotational movement. The bearing structures are suitably mounted on the floor 26 with the bearing structure 24 adjacent to the edge of the runner trough, the axis of the cylinder being at right angles with the runner trough.

The bent or angular nozzle N is rigidly secured to the discharge end of the cylinder 14 and may be integral therewith. The inlet part 27 of the nozzle is co-axial with the cylinder and the part 27' is in the vertical plane of the axis of the tapping hole and is bent so that the conical discharge end 28 may properly direct clay into the tapping hole. The cylinder is close to the floor 26 and when the tap hole is to be plugged, the cylinder is rotated to swing the nozzle from its idle position above the floor line (dotted lines Figure 3) to its discharging position with its end 28 in the runner trough at the mouth of the tap hole (full lines Figures 1, 2, and 3).

Suitable means may be provided for controlling the rotation of the cylinder and setting of the nozzle. As shown on Figure 3 a power cylinder 29 is provided in which a piston 30 travels and has the piston rod 31 extending from its ends through the heads 32 and 33 of the cylinder. The power medium may be air or fluid connected with the cylinder through piping 34 under suitable control mechanisms such as valves (not shown). The piston rod is interposed in a belt 35 traveling around pulleys 36 and 37, and belting 38 connects the pulley 36 with a sheave 39 on the intermediate member 16 secured to the cylinder. Thus by controlled application of power medium to the cylinder 29 the piston 30 therein is moved in one direction or the other for rotating the cylinder structure for swing of the nozzle into its discharging position, or into its idle position.

Referring to Figures 1 and 2, a supporting base 40 is mounted on the floor 26 adjacent to the bearing structure 23, this base supporting a housing part 41 to which the other housing part 42 is secured to provide a housing and bearing support for the hub 43 of a worm wheel 44. Above this housing is a transverse housing 45 journal-

ing a shaft 46 and enclosing a worm pinion 47 on the shaft 46 and meshing with the worm wheel 44. The housing part 42 has brackets 48 extending therefrom on which a driving source such as an electric motor 49 is mounted. The motor shaft carries a pinion 50 meshing with the gear 51 on the shaft 46, so that when the motor is running the worm wheel 43 will be rotated at reduced speed.

The shaft 18 of the piston 15 has threading 52 at its outer end and the worm wheel hub 43 is threaded to receive the shaft 18 so that when the worm wheel is turned the shaft 18 will be axially driven for movement of the piston 15 in the cylinder 14 for discharge of clay from the cylinder to and through the nozzle 27. Suitable means are provided to hold the shaft 18 against rotational movement. As shown a spline or key 53 is provided in the cylinder for engagement by a keyway 54 in the piston.

The cylinder 14 has an opening 55 through which clay may be charged into the cylinder, this hole being closed by a suitable cover 56 during operation of the cylinder. When the gun is to be used for a plugging operation, the motor 49 is operated for withdrawal of the piston to the inner end of the cylinder and then clay is charged into the cylinder through the opening 55. The power cylinder 29 is then operated for rotation of the gun cylinder and swing of the nozzle down into the runner trough with its end at the tapping hole 11, as shown in full lines of Figure 3, and then the motor 49 is operated for shift of the shaft 18 to force the piston 15 towards the outer end of the cylinder 14 for projection of the clay through the nozzle and into the tapping hole 11. After the nozzle has been in the tapping hole for a sufficient length of time to permit the soft clay to set, the power cylinder 29 is operated for rotation of the gun cylinder and swing of the nozzle into its idle position as shown by dotted lines on Figure 3.

In the arrangement shown in Figures 1 and 2, the driving motor and the transmission gearing is mounted on the stationary base 40 and only the gun cylinder 14 and the intermediate member 16 are rotated for swing of the nozzle.

In the modified arrangement shown on Figure 4 the stationary supporting base is omitted and the housing part 57 for the worm wheel forms part of the bearing hub 22 which is journaled in the bearing structure 23 and rotates with the intermediate member 16 and the cylinder 14. The other part 58 for the housing for the worm wheel supports the motor 49, and the housings 57, 58 support the worm housing 45, so that when the power cylinder 29 is operated, the cylinder 14, the intermediate part 16, and the motor and reduction gearing all rotate together for setting of the nozzle. To protect the threading 52 on the gun piston shaft, a tubular housing 59 is provided.

I have thus provided an improved structure and arrangement which will permit the gun to be mounted close up to the furnace at one side of the runner trough and with its axis at right angles to the runner trough, in which position the gun will not take up valuable floor space and will be protected against damage by splashing molten metal. The nozzle being comparatively short and of gradual bend, and directly connected to the cylinder end, the clay will be forced through the nozzle with minimum resistance, and the nozzle can be readily cleaned.

I have shown practical and efficient embodi-

ments of the features of my invention but I do not desire to be limited to the exact construction, arrangement and operation shown and described as changes and modifications may be made without departing from the scope of the invention.

I claim as follows:

1. A clay discharging structure for a blast furnace having a tapping hole and a runner trough extending therefrom, said structure comprising a single cylinder in front of the furnace with its discharge end adjacent to the side of the runner trough and with its axis at right-angles to the runner trough, a bent nozzle having its horizontal part rigidly secured to the discharge end of said cylinder in axial alignment therewith and having its discharge end within the vertical plane of the axis of the furnace tapping hole, an intermediate member providing at its outer end a head for the inner end of said cylinder, an outer bearing mounted on the floor in front of the furnace and directly adjacent to the runner trough for journaling the cylinder at its outer end, an annular bearing mounted on the floor in front of the furnace journaling the inner end in said intermediate member whereby said cylinder together with said intermediate member form a rotatable unit, a piston within said cylinder and a piston shaft extending therefrom through said intermediate member and said inner bearing, an electric motor stationarily mounted adjacent to the inner end of said inner bearing, a driving train between said motor and the inner end of said piston shaft connected to longitudinally reciprocate said shaft and piston for the discharge of clay from said cylinder and through said nozzle and into the furnace tap hole, and driving means connecting with said intermediate member for effecting rotation thereof for placing the nozzle end in clay discharge position or to a position away from the tapping hole and above the runner trough.

2. A clay discharging structure for a blast furnace having a tapping hole and a runner trough extending therefrom, said structure comprising a single cylinder located in front of the furnace with its discharge end adjacent to the side of the runner trough and with its axis at right-angles to the runner trough, a bent nozzle having its horizontal part rigidly secured to the discharge end of said cylinder in axial alignment therewith and having its discharge end within the vertical plane of the axis of the furnace tapping hole, an outer bearing mounted on the floor in front of said furnace directly adjacent to the runner trough and journaling the cylinder at its outer end, an intermediate member forming at its outer end an inner head for said cylinder, an annular inner bearing receiving and journaling the inner end of said intermediate member, a piston in said cylinder and a shaft extending therefrom through said intermediate member and said inner bearing, means holding said piston and shaft against rotational movement, the inner end of said piston shaft being threaded, a housing stationarily mounted on the floor in front of the furnace and adjacent to the inner end of said inner bearing, a worm gear within said housing threaded to receive the threaded end of said piston shaft, an electric motor mounted on said housing, a driving gear train extending between said motor and said worm wheel whereby said motor will effect longitudinal movement of said piston shaft and piston for discharge of clay from the cylinder through said nozzle and into the furnace tapping hole, and driving means connected

with said intermediate member for rotation of said member and cylinder for swinging of the discharge end of said nozzle into the runner trough in clay discharging position or for swing of the discharge end of the nozzle away from the tapping hole and above the runner trough.

3. A clay discharging structure for a blast furnace having a tapping hole and a runner trough extending therefrom, said structure comprising only a single cylinder which is located in front of the furnace with its discharge end adjacent to the side of the runner trough and with its axis at right-angles to the runner trough, a bent nozzle having its horizontal part rigidly secured to the discharge end of said cylinder in axial alignment therewith and having its discharge end within the vertical plane of the axis of the furnace tapping hole, an outer bearing mounted on the floor in front of the furnace directly adjacent to the runner trough for journaling the cylinder at its outer end, an intermediate

member providing at its outer end a head for the inner end of said cylinder, an inner bearing receiving and journaling the inner end of said intermediate member whereby said cylinder and intermediate member form a unit rotatable in said bearings, for locating said nozzle relative to the furnace tap hole, a piston in said cylinder and a shaft extending therefrom through said intermediate member, and driving means stationary mounted on the floor adjacent to the inner end of said inner bearing and having driving connection with said shaft to effect reciprocation of said piston for discharge of clay from the cylinder to said nozzle, and driving means coacting with said intermediate member for rotating said unit for swing of the nozzle for discharge of clay into the furnace tapping hole or for swing of the nozzle into position out of and above the runner trough.
